UNITED STATES PATENT OFFICE.

JOHN R. KASLER, OF MILLFIELD, OHIO.

MOTOR.

Application filed February 1, 1923. Serial No. 616,805.

To all whom it may concern:

Be it known that I, JOHN R. KASLER, a citizen of the United States of America, residing at Millfield, in the county of Athens 5 and State of Ohio, have invented new and useful Improvements in Motors, of which the following is a specification.

The object of the invention is to provide a motor of the internal combustion or explosive type having simplified means for controlling the intake and exhaust of the cylinders as compared with the more or less complicated valve mechanism of various types which are conventionally used in this 10 connection and which are objectionable by reason of the frequent and unavoidable disarrangement thereof, either relatively or as a unit; and with this object in view the invention consists in a construction and 15 combination of parts of which a preferred embodiment is shown in the accompanying drawings, wherein:—

Figure 1 is a side view,

Figure 2 is a transverse sectional view, 25 and

Figure 3 is a longitudinal sectional view taken horizontally of a motor constructed in accordance with the invention.

Figure 4 is a detail longitudinal sectional 30 view taken vertically through a portion of and in the plane of the controller shaft.

The engine block 10 in addition to containing the cylinders 11 is provided with a longitudinal bearing 12 extended parallel 35 with the series of cylinders and in communication with the latter by inlet and exhaust ports 13 and 14, and with said seat also communicate the intake and exhaust manifolds 15 and 16.

40 The port controlling element 17 which is revolvably mounted in said seat and is connected by timed gearing represented by the gears 18 and 19 with the crank shaft 20, carries packing rings 21 disposed at opposite sides of the planes respectively of the ports by which communication with the

cylinders is effected, said controller being provided with inlet and exhaust ports 22 and 23 for communication in proper timed relation with the cylinder ports in order 50 to secure the proper sequence in the explosions in the several cylinders.

This arrangement of port control ensures a fixed relation between the elements and a proper timed rotation of the controller 55 with relation to the crank shaft obviously will insure the proper feeding of the fuel and exhaust of the exploded charges without the disadvantages of noise and uncertainty attached to the operation of valve 60 mechanisms as now ordinarily employed in connection with motors of this type.

Having described the invention, what is claimed as new and useful is:—

A motor comprising a cylinder block 65 having its bore surrounded by a jacket compartment adapted to retain a cooling agent, a cap closing the end of the cylinder and provided with a jacket compartment adapted to retain a cooling agent, the cap being 70 provided at its under side with a port which is disposed between the jacket compartments of the cylinder and the cap, the cylinder being provided at its side and beyond the outer wall of its jacket compartment with a bearing which communicates with the said port in the cap, the cylinder also having an exhaust port passageway 75 passing through the jacket compartment of the cylinder and communicating with the bearing, a valve member journaled for rotation in the bearing and having ports adapted to register with the first mentioned ports and intake and exhaust manifolds 80 communicating with the interior of the bearing at points spaced from each other and at points spaced from the first mentioned port and the passageway.

In testimony whereof he affixes his signature.

JOHN R. KASLER.
